UNITED STATES PATENT OFFICE

MAX ESSER, OF BERLIN ZEHLENDORF MITTE, GERMANY

DESIGN FOR A BELL

Application filed January 14, 1930. Serial No. 34,130. Term of patent 3½ years.

To all whom it may concern:

Be it known that I, MAX ESSER, residing at 38 Berlepschstrasse, Berlin Zehlendorf Mitte, have invented a new, original, and ornamental Design for a Bell, of which the following is a specification.

The figure is a front elevation of a bell, showing my new design.

What I claim is:

The ornamental design for a bell, as shown. In testimony whereof I affix my signature.

PROF. MAX ESSER.
